US0D1030985S

(12) **United States Design Patent** (10) Patent No.: **US D1,030,985 S**
(45) Date of Patent: ** Jun. 11, 2024

(54) **ANODE ASSEMBLY FOR A HEAT EXCHANGER**

(71) Applicant: **Rheem Manufacturing Company**, Atlanta, GA (US)

(72) Inventors: **Robert Stuart Glass**, Tuscaloosa, AL (US); **Terence Sean Doyle**, Oak Park, CA (US); **Juan Carlos Montanez**, Oxnard, CA (US); **Owen Lewis Joyce**, Cary, NC (US); **William Kevin Carpenter**, Warrensville, NC (US); **Timothy Curtis Simmons**, Charlotte, NC (US); **Alexander Adam Papp**, Raleigh, NC (US)

(73) Assignee: **Rheem Manufacturing Company**, Atlanta, GA (US)

(**) Term: **15 Years**

(21) Appl. No.: **29/829,147**

(22) Filed: **Mar. 3, 2022**

(57) **CLAIM**

The ornamental design for an anode assembly for a heat exchanger, as shown and described.

DESCRIPTION

FIG. 1 is a top perspective view of an anode assembly for a heat exchanger.

FIG. 2 is a bottom perspective view thereof; and, FIG. 3 is a sectional view thereof taken along section line A-A of FIG. 1.

The broken lines shown depict the portions of the anode assembly for a heat exchanger that form no part of the claimed design.

The long dash-short dash broken lines in FIG. 1 represent the direction of sight in the sectional view and form no part of the claimed design.

1 Claim, 3 Drawing Sheets
